UNITED STATES PATENT OFFICE.

JUSTUS J. SMITH, OF NEW YORK, N. Y.

CABLE-HANGER.

SPECIFICATION forming part of Letters Patent No. 740,326, dated September 29, 1903.

Application filed February 4, 1903. Serial No. 141,901. (No model.)

To all whom it may concern:

Be it known that I, JUSTUS J. SMITH, a citizen of the United States, residing at New York, in the borough of Manhattan and State 5 of New York, have invented certain new and useful Improvements in Cable-Hangers; and I do hereby declare the following to be a full, clear, and exact description of the invention, such as will enable others skilled in the art to 10 o which it appertains to make and use the same.

My invention relates to improvements in cable-hangers intended to support electric cables from messenger-wires. In such devices it is important to secure a hanger that will 15 hold firmly, may be readily applied or removed, and is of sufficient strength, cheapness, and durability.

My invention will be understood by reference to the accompanying drawings, in which 20 the same parts are indicated by the same letters throughout the several views.

Figure 1 is a perspective view showing the hanger as applied to the cable and the messenger-wire, these two latter being shown in 25 dotted lines. Fig. 2 is an end elevation of the device shown in Fig. 1. Fig. 3 shows the hook and lock detached from the strap, and Fig. 4 is a detail.

A represents a strap, preferably of metal, 30 such as zinc.

B represents the link, which is held in a bight in one end a of the strap A. To secure better hold, the strap may where folded be indented at a' . This link B projects beyond 35 the edges of the strap, as shown in Fig. 1. The link B is preferably broken, as at b , Fig. 3, and the strap is preferably hammered into the space between the ends, as shown at a' , whereby better holding is secured. The opposite end a' of the strap is looped over the bar c of the double hook C. This hook has 40 two arms, which are curved, as at c' , and terminate in tongues c' , which tongues are adapted to pass through the U-shaped portion of the loop, which projects beyond the edges of 45 the strap, as shown in Fig. 1.

D represents the messenger-wire, and E the cable.

The hanger is applied as follows: The end 50 a of the strap being bent over the link B and indented or not, as preferred, the opposite end a' is bent over the bar c of the double

hook C and is lapped far enough so that when in position it will rest on the messenger-wire, as shown in Fig. 1. The strap is drawn taut 55 around the cable E, as shown in Fig. 1, is passed back of and then over the messenger-wire D, the tongues c' are inserted in the link B, and the hook is pushed forward to the position shown in Fig. 1. The weight of the 60 cable will now tend to cause the hook and link to bind the strap firmly around the cable E, while at the same time the pressure on the folded part a' of the strap will cause the same to bind and prevent slipping. Thus it 65 will be seen that the hanger once applied will tend to lock itself firmly to the cable, and yet will slide freely along the messenger-wire.

In order to remove the hanger, it is only necessary to lift the cable slightly, to push 70 the tongues c' out of engagement with the loop B, and the strap may be readily removed from the cable and from the messenger-wire.

Having thus described my invention, what 75 I claim, and desire to secure by Letters Patent of the United States, is—

1. The combination with a cable and a messenger-wire, of a link, a strap folded over the central portion of said link, and having its 80 free end bearing against said cable with a fold in the other end of said strap, having its free end bearing on said messenger-wire, and a double hook pivoted in said latter fold, and having curved tongues projecting through 85 the ends of said link at either side of said strap, substantially as described.

2. A cable-hanger, comprising a link made of a single piece of wire with its ends spaced apart at approximately the center of one side 90 of said link, a strap folded over the central portion of said link, and having the fold pressed into the space between the ends of said wire, and a double hook secured in a fold in the other end of the strap and provided 95 with curved tongues passing through the ends of the link projecting beyond the sides of the strap, substantially as described.

In testimony whereof I affix my signature in presence of two witnesses.

JUSTUS J. SMITH.
